CURTAIN FOR FOCAL PLANE SHUTTERS

Irving W. Doyle, Massapequa, and Carl V. Johnson, Kew Gardens, N. Y., assignors to Fairchild Camera and Instrument Corporation, Jamaica, N. Y., a corporation of Delaware

Application November 2, 1944, Serial No. 561,556

3 Claims. (Cl. 95—57)

1

This invention relates to a curtain for a focal plane shutter.

As fixed slit focal plane shutters are capable of speeds in excess of a thousandth of a second, their curtains must be capable of withstanding substantial stresses and forces to which they are subjected throughout a complete cycle of operation. During the winding portion of the cycle, the full bias of the shutter spring is exerted on the curtain which, for the sake of manufacturing expediency, is customarily made in two parts joined together at the slit. When an exposure is made at high speed, the full force of the spring is suddenly exerted on the curtain so as to sweep its slit across the focal plane. Although the curtain and its associated parts are relatively light in weight, they have, however, sufficient inertia and gain sufficient momentum, to cause undesirable exposure conditions. These conditions often result in improperly exposed negatives, particularly in the case of aerial photography, where in many cases extreme accuracy of reproduction is prerequisite.

Thus, if the width of the curtain slit varies during the exposure, the negative is not uniformly exposed. Inasmuch as the curtain slit is customarily formed by spaced relatively rigid strips of metal or the like, these strips, because of their necessary light weight, are characterized by a certain amount of resiliency. Thus when the curtain, and accordingly the strips, move at high speed across the focal plane, the force of the shutter spring may be transmitted through the curtain to one or both of the slit forming strips, thereby causing relative movement between the strips during their exposure movement.

It is accordingly among the objects of this invention to provide a curtain for a focal plane shutter which, while simple, inexpensive and rugged in construction, yet overcomes the above disadvantages in addition to others in an efficient and practical manner.

The invention accordingly consists in the features of construction, combinations of elements, and arrangements of parts, as will be exemplified in the structure to be hereinafter described, and the scope of the application of which will be indicated in the following claims.

In the drawing, wherein there is shown one form of the invention,

Figure 1 is a top plan view of the shutter with a portion broken away to show a driving spring;

Figure 2 is a fragmentary top plan view of one of the shutter curtains;

2

Figure 3 is a substantially enlarged section taken along the line 3—3 of Figure 1; and

Figure 4 is a substantially enlarged section taken along the line 4—4 of Figure 1.

5 Similar reference characters refer to similar parts throughout the various views of the drawing.

In Figure 1, a shutter is generally indicated at 10 and includes a pair of curtains 11 and 12, joined together at their ends which are spaced a suitable amount to provide an exposing slit 13. The opposite ends of curtains 11 and 12 are secured to rollers 14 and 15, one or the other of which may include a conventional operating spring 14a which, when the shutter is released for operation, draws slit 13 across the focal plane aperture which lies between rollers 14 and 15.

Curtains 11 and 12 are identical in all respects, and accordingly for brevity we have shown in 20 Figure 2 curtain 12. This curtain may be formed of any suitable opaque material, preferably a finely woven fabric which may be suitably treated to assure complete opacity. At the slit forming end of the curtain are a pair of tabs 16 and 17 by which curtain 12 is attached to curtain 11 (Figure 1) in a manner to be hereinafter described, to form slit 13.

Referring back to Figure 2, the fabric between tabs 16 and 17 is slit as at 40 and 41 and 30 is cut on a radius to provide a curved end portion 18 to which is fastened a metal strip 19. Strip 19 is U-shaped in cross section and accordingly, as may be seen in Figure 4, comprises top and bottom flaps 20 and 21, and a bight 22. 35 The ends of strip 19 (Figure 1) are so formed as to provide spaced attaching ears as, for example, ears 23 and 24 (Figure 3), through which a rivet 25 extends to fasten the end of the strip to curtain tab 17 of curtain 12, as well as curtain tab 16a of curtain 11. The other end of slit strip 19 (Figure 1) is similarly attached to the other overlying tabs of curtains 11 and 12. The portion of strip 19 between its ends has disposed therewithin the curved edge 18 (Figure 4) of curtain 12, which may be wrapped around a small rod 26 which lies within the bight 22 of the strip. When this curved edge of the curtain is installed about rod 26 within the strip, the central portion of the curtain is drawn away from 45 the strip, while the ends of the curtain edge are held so that loose folds 27 (Figure 1) of the curtain fabric are formed centrally thereof. The edge of the curtain may be secured within strip 19 in any suitable fashion, as by cementing the 50 fabric therewithin.

Curtain 11 is similarly attached to a strip 28, the ends of which are fastened to the curtain tabs in the same manner as described hereinabove with respect to the joint shown in Figure 3. Thus the overlying curtain tabs 16a and 17 are held against separation by two rivets 25 (Figure 1) and the joint thus formed has stitched thereto overlying and underlying strips 29 and 30 (Figure 3) of any suitable material, these strips being stitched to the curtain tabs as shown at 31 in Figure 1.

It will now appear that the two curtains 11 and 12 are securely fastened together at the ends of slit 13, and also that the strips 19 and 28 which form slit 13 are fastened to the curtains in accurately dimensioned spaced relationship, wherein they are held substantially immovable relative to one another by reason of the nature of their attachment to the curtains, and by reason of their inherent substantial rigidity resulting from their U-shaped cross section, as well as the rods, such as rod 26 (Figure 4) lying in the bight of each. Curtain 11 is, of course, fastened to strip 28 in the same manner as described with respect to curtain 12 and strip 19, so that loose folds 32 of material are formed at the central portion of the curtain adjacent the edge thereof.

When curtains 11 and 12 are mounted on rollers 14 and 15, the shutter operating spring in one of the rollers draws the two curtains taut so that they lie flat adjacent the focal plane. Through the provision of the loose portions or folds 27 and 32 in the curtains the tension of the shutter spring is to a substantial extent absorbed by the fabric of the curtains before being exerted on the central portions of strips 19 and 28. Otherwise, the spring bias would bow the central portions of the strips away from one another, thus imparting to the opposite edges of slit 13 a curvature rendering the slit width non-uniform. By the same token, the sudden pressure of the shutter spring on the curtain when an exposure is made is substantially absorbed by these loose curtain portions, with the result that there is little or no relative movement between the slit forming strips 19 and 28 at the beginning of or during exposure operation of the curtains.

Thus it will be seen that we have provided a focal plane shutter curtain which attains the several objects set forth hereinabove in a thoroughly practical and efficient manner.

We claim:

1. In a focal plane shutter curtain, in combination, a relatively rigid straight slit forming strip, a flexible cloth curtain having slit and roller attaching edges, and means for attaching the slit edge of said curtain to said strip, the

length of said curtain while motionless at its longitudinal center line being greater than the length of said curtain along lines spaced transversely of its center line, the greater length of said curtain along its longitudinal center line being created through the provision of a surplus of material adjacent to and extending away from the slit edge of the curtain where it is attached to said strip.

2. A shutter curtain according to claim 1 wherein the slit forming strip comprises a rod extending transversely of the curtain and having wrapped thereabout the leading edge of said curtain, said leading edge being arcuate in the direction of its movement during exposure operation, said slit forming strip also including an element extending transversely of the curtain and embracing said rod and those portions of the leading edge of the curtain adjacent to the rod, said arcuate curtain edge being so disposed in relation to a straight edge of said element as to be substantially parallel thereto, whereby there is created a surplus of curtain material adjacent said slit forming strip along the central portions thereof.

3. In a focal plane shutter curtain, in combination, a relatively rigid straight slit forming strip, a cloth curtain member having slit and roller attaching edges, and means for attaching the slit edge of said curtain member to said strip, said roller attaching curtain edge being parallel to said strip, the length of said curtain while motionless being greater along its longitudinal center line than the length of the curtain along lines spaced transversely of its center line whereby there are created loose folds of curtain fabric between said slit and roller attaching edges.
